(57) **CLAIM**

The ornamental design for a climbing rope with position markers, as shown and described.

DESCRIPTION

FIG. 1 is a front elevational view of a climbing rope with position markers showing my new design;

FIG. 2 is a rear elevational view thereof;

FIG. 3 is a right side view thereof; and,

FIG. 4 is a right side view in an alternate configuration.

The climbing rope with position markers is shown with a symbolic break in its length. The appearance of any portion of the article between the break lines forms no part of the claimed design. In the drawings, the randomly spaced stippling is shown merely for the purpose of illustrating surface shading and does not represent any particular color, material, texture or finish.
